UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 27,237, dated June 22, 1897.

Application filed May 6, 1897. Serial No. 635,427. Term of patent 7 years.

To all whom it may concern:

Be it known that I, WILLIAM C. CODMAN, a subject of Her Majesty the Queen of Great Britain, residing at Providence, in the county 5 of Providence and State of Rhode Island, have invented and produced a new and original Design for the Handles of Spoons, Forks, and Similar Articles, of which the following is a specification, reference being had to the accompanying drawings, forming part thereof.

Figure 1 is a view of the obverse side of the handle, showing my design connected with the bowl of a spoon in solid lines and indicating the tines of a fork in broken lines. Fig. 2 is 15 a view of the reverse side of the handle, showing my design in connection with the bowl of a spoon.

The leading features of my design consist in the ornamentation at the juncture of the 20 handle with the article to which it is connected, the entwined scrolls of the marginal beads at the junction of the blade with the stem of the handle, and the two scrolls extending from the honeysuckle rosette at the 25 upper end of the handle.

In the drawings, A designates the bowl of the spoon, B the stem of the handle, and C the blade of the handle. On both the obverse and reverse sides of the handle the edges of 30 the bowl curve inward and merge into the foliations d d. From these extend the raised marginal beads e to the leaves f, which extend from the scrolls g downward. The stem h

curves upward and inward from each side and supports the central ornament i. The 35 marginal bead k terminates in a scroll inclosing the stem h. The upper end of the handle is ornamented with the central rosette l, from each side of which extend the raised scrolls m, terminating on the margin of the 40 blade in the foliations n. On the obverse the ornamentations inclose the convex panels o on the blade of the handle p at the junction of the stem and the blade and panel q on the stem, while on the reverse the panel q is 45 omitted.

From the lower end of the handle two scrolls extend inward, and from them extends the scrolled and foliated ornament r over a portion of the article to which the handle is connected. The ornamentations extend above the surface of the panels and present to the eye the appearance of boldly-carved foliated scrolls. 50

Having thus described my invention, what 55 I claim as new, and desire to secure by Letters Patent, is—

The design for a handle for spoons, forks and similar articles herein shown and described. 60

In witness whereof I have hereunto set my hand.

WILLIAM C. CODMAN.
